UNITED STATES PATENT OFFICE.

JÖNS MONSON, OF NEW YORK, N. Y.

TOY.

Original application filed August 25, 1925, Serial No. 52,308. Divided and this application filed April 30, 1926. Serial No. 105,719.

This invention relates to amusement and pastime games and has reference to spinning toys, and is a division of application 52,308, filed Aug. 25, 1925.

5 The purpose of the invention is to provide a spinning toy that is spun on its edge and offers a great diversity of chances.

The toy consists of a round disc-shaped body thickest at the center. Its two opposite 10 sides are divided in plane triangular facets radiating from the center. The facets are the resting bases of the toy, and when it is spun on its edge, it may come to rest on any facet on any side. The facets may be opposite each 15 other on the opposite sides or alternating as desired. The edge may be square, round or sharp as desired. The toy has game indicia on the opposite sides.

Referring to the accompanying drawing: 20 Figure 1 is a side elevation of the toy.

Figure 2 is a section in the line 1-1 of Fig. 1.

Figure 3 is a section in the line 2-2 of Fig. 1.

25 Figure 4 is a side elevation of a modified form of the toy.

Figure 5 is a section in the line 4-4 of Fig. 4.

Figure 6 is a section in the line 5-5 of 30 Fig. 4.

In the drawing, Figures 1 to 3, inclusive, show the disc-shaped toy thickest at the center and its opposite sides with the plane triangular facets 3 and game indicia. Both sides are shaped alike.

Figures 4 to 6, inclusive, show the modified form of the disc-shaped toy thickest at the center and its opposite sides with the plane triangular facets 3 and game indicia. Both sides are shaped alike.

I claim:

1. A spinning toy comprising a circular disc-shaped body thickest at the center having its two opposite sides divided in plane triangular facets radiating from the center, 45 and these facets being the resting bases of the toy.

2. A spinning toy comprising a circular disc-shaped body thickest at the center having its two opposite sides divided in plane 50 triangular facets radiating from the center, these facets being the resting bases of the toy, and the toy having game indicia on its opposite sides.

Signed at New York, in the county of New 55 York and State of New York, this 28th day of April A. D. 1926.

JÖNS MONSON.
